UNITED STATES PATENT OFFICE.

NORMAN A. LICHTY, CLAUD S. LICHTY, AND HENRY F. CAMPBELL, OF WATERLOO,
IOWA, ASSIGNEES TO LICHTY METAL PRODUCTS COMPANY, OF WATERLOO,
IOWA, A CORPORATION OF IOWA.

VENTILATOR.

1,309,037.

Specification of Letters Patent.

Patented July 8, 1919.

Application filed July 15, 1918. Serial No. 244,858.

To all whom it may concern:

Be it known that we, NORMAN A. LICHTY, CLAUD S. LICHTY, and HENRY F. CAMPBELL, citizens of the United States, residing at 5 Waterloo, in the county of Blackhawk and State of Iowa, have invented certain new and useful Improvements in Ventilators, of which the following is a specification.

Our invention relates to improvements in 10 ventilators, and particularly to ventilating devices applied for structures for housing stock, particularly hogs, and the object of our improvements is to supply a wind-directed cowl for a ventilating-flue, balanced, 15 and mounted rotatably on anti-friction means to easily and quickly respond to air movements of small magnitude, directed so that an efficient suction is set up thereby in the ventilating-flue for thoroughly ventilating and aerating the building.

This object we have accomplished by the means which are hereinafter described and claimed, and which are illustrated in the accompanying drawings, in which Figures 25 1 and 2 are respectively elevations of our ventilator, taken from points looking toward the funnel thereof, and from a point looking at the opposite side of the ventilator; Fig. 3 is an elevation of the ventilator taken 30 from a position at an angle of ninety degrees from said Fig. 1; Fig. 4 is an elevation of said ventilator similar to said Fig. 1, but with parts removed or broken away to disclose the interior mounting of the cowl 35 on the ventilating-flue; Fig. 5 is a plan view of the ventilating-flue showing the cowl in horizontal section, and Fig. 6 is an enlarged detail view of the cowl-spindle and the anti-friction bearing parts there- 40 for, parts being shown in central vertical sections.

In the drawings, similar numerals of reference denote corresponding parts throughout the several views.

45 Our improved ventilator has the hollow rectangular ventilating-flue basal part 1 terminating upwardly in a conical part 2 and a cylindrical part 3, the latter being outwardly reinforced by a flat ring 4. The 50 basal part 1 may have two opposite sides cut away angularly at 13 to be conformed to the pitch of a roof on which it is mounted over a flue or roof opening.

The cowl is of the elbow-shaped type,

having a semi-cylindric wall 6 whose sides 55 extend out straight in parallelism to form a funnel directed laterally terminating with flaring edges 8.

A counter-weight 7 is fixed on the back of the wall 6 to balance the cowl. The top 60 of the cowl is formed of a single plate 9, which is planar in type and curved upwardly to the upper edge of the funnel, a median vane 10 being mounted longitudinally upon the top of the cowl and braced 65 by oppositely-extending rods 11.

A wire netting 12 is positioned across the mouth of the funnel of said cowl, to keep out birds.

The cowl wall 6 is mounted upon a horizontal plate 29, having a circular opening 30 about the neck-piece 3 of the ventilating-flue, and connected to said plate by a ring 5.

The cowl is mounted rotatably upon the ventilating-flue as follows: The numeral 14 75 denotes a cross-bar crossing the neck 3 diametrically and having its ends turned up and secured to the inner wall of said neck, and said bar is medially orificed.

The numeral 15 denotes a step-bearing 80 whose lower end is diminished and seated in said orifice, and this bearing contains an anti-friction ball 24. The exterior periphery of the bearing is threaded and seated in the lower end of a vertical cylinder 16. 85 A sleeve-bearing 17 is in threaded junction with the upper end of the cylinder 16, and its upper exteriorly threaded end is passed through bars 18 and a sleeve-ring 19 connected to said bars by bolts 27 and nuts 28. 90 Cross-bars 20 extend across the cowl with their ends secured to the inner wall thereof, and are orificed at their crossing to receive a spindle 21 fixedly pendent from the top 9 of said cowl, the upper end of said spindle 95 having a threaded socket 23 to receive a screw 22 securing it to said cowl detachably.

The cross-bars 20 and the sleeve-bearing 17 receive said spindle rotatably, the lower diminished end of the spindle depending 100 into the cylinder 16 in spaced relation, a cross-pin 25 serving to prevent its egress upwardly, by impinging on the lower end of the sleeve 17. The lower end of the spindle rests upon the ball 24. Within said 105 sleeve 17, the middle part of said spindle is diminished at 26 to diminish frictional contact with the inner wall of the sleeve.

It will be seen that the entire weight of the cowl is thus poised on the anti-friction ball 24, and that a very slight impulsion will rotate the cowl to its position in line 5 with the impelling air-current.

The curvilinear planar top of the cowl also permits the air-current to pass smoothly and evenly over it to exercise equal action on the vane 10, and thus a 10 vacuum is engendered before the funnel of the cowl, which draws up air through the ventilating-flue, to properly ventilate and aerate the building below.

Having described our invention, what we 15 claim as new, and desire to secure by Letters Patent, is:—

1. A ventilator, comprising a ventilating-flue, and an elbow-shaped cowl rotatably mounted thereon, the top of the cowl being

planar and sloped curvilinearly upwardly 20 toward the upper edge of the funnel of the cowl.

2. A ventilator, comprising a ventilating-flue, an elbow-shaped cowl having a vane thereon, a step-bearing mounted fixedly centrally within said flue, an anti-friction ball positioned in the step-bearing, a sleeve-bearing surmounting and in communication with the step-bearing, and a pendent spindle fixedly centrally mounted in said cowl and positioned rotatably in said step- and sleeve-bearing and stepped on the ball in the step-bearing. 25 30

In testimony whereof we affix our signatures.

NORMAN A. LICHTY.

CLAUD S. LICHTY.

HENRY F. CAMPBELL.
